SPARK PLUG WITH DETACHABLE ELECTRODE

August Eugene Anderson, Montclair, N. J.

Application June 17, 1932. Serial No. 617,899

2 Claims. (Cl. 123—169)

My invention relates to a spark plug for internal combustion engines, and more particularly to the manufacture and assembling of the so-called ground electrode therefor. This invention forms a further development and improvement of the spark plug shown and described in my copending application Serial No. 604,592, filed April 11, 1932, for Spark plug. As in said copending application a special recess or chamber is here provided for the spark gap, so that the ends of both electrodes are completely concealed therein and not exposed to the direct effect of the compressed charge of the combustion gases. By this arrangement overheating of the electrodes is prevented with consequent pre-ignition.

The ground electrode in accordance with the present invention consists of a straight piece of wire with a hook at its lower end and inserted in the plug so as to be detachable both from the porcelain insulator and the metal body of the plug. In other words the ground electrode forms a separate element from the porcelain and the body.

In the accompanying drawing one embodiment of the invention is illustrated and

Fig. 1 is a vertical axial section of the spark plug.

Fig. 2 is a horizontal section of the spark plug along line 2—2 of Fig. 1, and,

Fig. 3 is a fragmentary side elevation of the lower end of the dielectric or porcelain insulator.

My spark plug consists of the usual main parts as will be seen in the drawing, namely the metal body 10, the porcelain insulator 11 with the central or main electrode 12, the securing cap 13 threaded in the top of the plug 10 and the detachable ground electrode 14.

The dielectric or porcelain 11 is provided with a central enlargement 15 having an upper bevelled surface 16 carrying an upper copper gasket 17 engaging the lower end of the cap 13. Similarly the lower bevelled surface 18 of the porcelain enlargement rests on the lower gasket 19, lodged in the corresponding, bevelled seat 20 in the body 10.

The porcelain terminates with a narrow shank 21 extending downwardly substantially to the lower end of the hollow end portion 22 of the metal body with sufficient clearance around said shank to permit expansion thereof. An annular ledge 23, having a smaller opening 28 than the outer diameter of the shank is provided on the end portion 22, for the purpose that in case the shank should break, it cannot fall out of the metal body 10 but be held therein by said ledge 23.

The shank 21, which is preferably cylindrical, has on one side a narrow groove or a flattened surface 24 extending nearly its full length to within a short distance from its bottom edge,

where a small radially directed hole 25 is provided and reaching into the cylindrical chamber 26 formed in the porcelain shank 21. This hole accommodates the hooked end or short arm 27 of the L-shaped electrode 14, which lies with its long arm along the flat surface 24 of the shank but preferably spaced from the inner surface of the end portion 22 of the metal body 10. The upper end of the ground electrode reaches up to the shoulder 18 of the porcelain and makes contact with the metal body 10 through the intermediary of the gasket 19.

It can be clearly seen that the grounded electrode is a separate unit and as it is not permanently attached to any other part of the spark plug, it is obvious that an electrode made in this manner has the advantages of saving in material and costs as no expensive dies are needed. It is here only necessary to take an ordinary electrode wire of the proper size and bend one end at right angles to fit into the hole provided therefor in the insulator to hold it in place when the lower gasket is placed over ground electrode to make electrical connection, when the spark plug is assembled as shown in my drawing.

Another object in making and assembling the ground electrode wire in this manner, is that any standard gasket on the market, of the proper size can be used without any alteration to the gasket or grounded electrode.

It is evident that many changes in the details and construction of the device may be made under the scope of the claims, and that these may be varied widely without departing from the spirit of the invention.

Another object and reason for making and assembling the ground electrode in this manner, is for the sake of convenience. In the case for instance that the ground electrode should burn away too far, thus causing the motor to miss, an emergency repair could then easily be made without difficulty, by taking a pair of pliers and a wire of the proper size to fit through the hole in the insulator, and bend to a hook on one end thereof and cut the wire off to the proper length and then reassemble the spark plug. The motorist would then be ready to travel many miles with this temporarily repaired plug.

I claim:

1. In a spark plug comprising a hollow metal body member, a dielectric core member seated therein and held firmly by a cap and standard gaskets, a shank at the lower end of said dielectric spaced from the side wall of the body member and provided with a downwardly open spark chamber, a main electrode suitably secured in said core member projecting with its spark point into the spark chamber and a detachable ground electrode having two straight arms, one of said arms being placed alongside the shank in the

- space formed between the shank and the wall of the body member, and the other arm forming an inwardly directed spark point on said ground electrode projecting into the spark chamber 5 through a suitable aperture provided in said shank, contact between said body member and ground electrode being made through the intermediary of one of said gaskets adapted to clamp said ground electrode in position.
- 10 2. In a spark plug comprising a hollow metal body member, a dielectric core member seated therein and held firmly by a cap and standard gaskets, a shank at the lower end of said dielectric spaced from the side wall of the body member 15 and provided with a downwardly open spark chamber, a main electrode suitably secured in said core member projecting with its spark point
